G. A. Corser.
Bed Plate for Paper Engine.
N° 43,070. Patented Jul 7, 1864.

UNITED STATES PATENT OFFICE.

GEORGE A. CORSER, OF LEICESTER, MASSACHUSETTS, ASSIGNOR TO
HIMSELF AND ANTHONY HANKEY.

IMPROVEMENT IN BED-PLATES FOR PAPER-MILL ENGINES.

Specification forming part of Letters Patent No. 43,070, dated June 7, 1864.

To all whom it may concern:

Be it known that I, GEORGE A. CORSER, of Leicester, in the county of Worcester and State of Massachusetts, have invented certain new and useful Improvements in Bed-Plates for Paper-Mill Engines; and I do hereby declare that the following is a full, clear, and exact description of the construction and operation of the same, reference being had to the accompanying drawings, in which—

Figures 1 and 2 represent perspective views of my said improved bed-plate. Fig. 3 represents a cross-section through the same. Fig. 4 represents a top view of a bed-plate, herein-after to be referred to.

The nature of my invention consists in the production of an angular bed-plate for paper-mill engines, which will permit the stock to enter and leave the same in an even and uniform manner, and without causing undue wear upon any particular point thereof.

In the application of angular bed-plates to paper-mill engines the difficulty occurs that the stock is crowded into the angles of the converging plates, where, owing to its accumulation, the plates are worn out at these points and the stock passes in bunches. In the old angular elbow-plate the plates thus wear out at their centers, and to remedy this various improvements thereon were made—such, for instance, as the construction of a zigzag angular plate, (represented in red lines at Fig. 4,) but in that plate the stock is crowded into each angle at *a*, and consequently wears the plates out in these places, causing the stock to pass out in bunches. These difficulties are entirely obviated in my bed-plate, in which I use two sets of angular plates firmly secured together, and which plates are arranged in such a manner that the angles of one set are inverted in relation to the angles of the other set.

To enable others skilled in the art to make and use my invention, I will proceed to describe its construction and operation.

b represents a number of elbow or angular plates, made of steel, and having an angular bend at or near their centers; or each plate may be made of two straight pieces, which are set toward each other at an obtuse angle.

c represents an equal number of angular plates identical in construction with the plates *b*, but so placed that their angles *d* are inverted in relation to the angles of the plates *b*. The ends of the corresponding plates in the two sets are fitted nicely together, as shown at *g*, and a wood filling, *h*, is inserted between each two consecutive plates, so as to keep those plates separated. The angular plates and wood fillings are securely fastened together by means of two outside plates, *A*, and screw-bolts *B*, and thus constitute a solid bed-plate.

In using the bed-plate the wood fillings *h* wear away, leaving the upper edges of the steel plates sharp, with a clear space between each consecutive plates, which, in conjunction with the revolving cutting cylinder, reduce the stock to pulp.

By reference to Fig. 1 it will be noticed that the stock in coming in contact (in the direction of the arrows) with the plates *b*, which diverge toward the ends of the bed-plate, is spread toward said ends, but in passing said plates *b* and in coming in contact with the plates *c*, which converge toward the center, it is crowded to the same extent toward said center, and the result is that the stock will leave the plates *c* at or very near at the same point from the center where it entered the plates *b*, and it is thus worked in an even and uniform manner through the entire plate without causing undue wear on any particular point thereof.

Fig. 2 represents a modified arrangement of angular plates in which the same principle as above explained is carried out, the angles of one set of plates being inverted toward those of the other set, and the result of the operation is the same.

Having thus fully described the nature of my invention, what I claim herein as new, and desire to secure by Letters Patent, is—

1. An angular bed-plate for working paper-stock, composed of two or more sets of angular plates, when said plates are arranged in such a manner that the angles of the adjoining sets are inverted in relation to each other, substantially in the manner and for the purposes described.

2. The combination of the angular metal plates *b c*, as herein arranged, and wooden fillings *h*, with the side plates, *A*, arranged in relation to each other, substantially as and for the purposes set forth.

3. The combination, with the angular plates for paper-engines, arranged as herein de-

scribed, of the parallel side plates, *A A*, in the manner and for the purpose herein set forth.

GEORGE A. CORSER.
